UNITED STATES PATENT OFFICE.

HENRY SHERMAN, OF LUCTOR, KANSAS, ASSIGNOR OF ONE HALF TO JACOB POPPEN AND ALBERT VAN DIEST, OF SAME PLACE.

KEEPER FOR THE LOOSE ENDS OF STRAPS.

SPECIFICATION forming part of Letters Patent No. 391,763, dated October 23, 1888.

Application filed June 15, 1888. Serial No. 277,173. (No model.)

To all whom it may concern:

Be it known that I, HENRY SHERMAN, a citizen of the United States, residing at Luctor, in the county of Phillips and State of Kansas, have invented a new and useful Improvement 5 in Keepers for the Loose Ends of Straps, of which the following is a specification.

My invention relates to keepers for the loose ends of straps, as the tug strap, the stirrup-10 straps, and other similar parts of harness, having for its object to provide a simple, cheap, and easily-applied device which will securely hold the strap in place; and it consists in a certain novel construction and arrangements, 15 fully set forth hereinafter in connection with the accompanying drawings, wherein—

Figure 1 is a perspective view of a keeper embodying my invention applied in the operative position to a strap. Fig. 2 is a similar 20 view thereof detached from the strap. Fig. 3 is a view of a slightly-modified form.

Referring to the drawings, A designates the improved keeper, which is struck from a single sheet of metal, and consists of the base-25 plate B and the rectangular loop C, arranged thereon. This loop comprises the sides c c, perpendicular to the base-plate, and the inward-extending fingers D D, which meet at their inner ends and are secured together by 30 solder, rivets, or other suitable means. The base-plate is provided with ears E E, having apertures e e therein, through which may be

passed rivets or their equivalents to affix the keeper to the strap.

Fig. 3 shows a modified form in which the 35 inward-extending fingers do not meet and are allowed to remain free this being in some cases preferable. The apertured ears may be omitted and an aperture in lieu thereof may be formed in the base-plate to receive the se- 40 curing-rivet or equivalent device.

This invention is simple and will hold the 45 end of the strap securely in place without chafing or cutting it, and it is easily applied to the strap.

Having thus described my invention, I 45 claim—

The herein described keeper for the loose ends of straps, consisting of a metal base-plate, B, having the integral perforated ears E E 50 above and below, and the integral rectangular loop at right angles to said ears, which loop is composed of a portion of the base-plate, the sides C, and the inwardly-standing triangular fingers D, secured together at their ends by 55 rivets or otherwise, substantially as specified.

In testimony that I claim the foregoing as my own I have hereto affixed my signature in presence of two witnesses.

HENRY SHERMAN.
